UNITED STATES PATENT OFFICE.

LUDWIG L. BLAKE, OF SOUTH BEND, INDIANA, ASSIGNOR TO F. C. DAVIDGE & CO., F. C. DAVIDGE, PROPRIETOR, OF TORONTO, CANADA.

DESIGN FOR WALL-PAPER.

46,558.

Specification for Design.

Patented Oct. 20, 1914.

Application filed July 29, 1914. Serial No. 853,949. Term of patent 3½ years.

To all whom it may concern:

Be it known that I, LUDWIG L. BLAKE, a citizen of the United States, residing at South Bend, in the county of St. Joseph and State of Indiana, have invented a new, original, and ornamental Design for Wall-Paper, of which the following is a specification, reference being had to the accompanying drawing, forming a part thereof, and in which the figure is a plan view of a portion of wall-paper illustrating my new design.

The drawing shows the design in reduced scale; the coloring of the various portions being subject to variance at will, is merely indicated by the shading.

I claim—

The ornamental design for wall paper as shown.

LUDWIG L. BLAKE.
